UNITED STATES PATENT OFFICE.

JOHN THOMAS COONEY, OF DENVER, COLORADO.

MILK-BOTTLE TOP.

1,308,226.

Specification of Letters Patent.

Patented July 1, 1919.

Application filed December 27, 1918. Serial No. 268,567.

To all whom it may concern:

Be it known that I, JOHN T. COONEY, a citizen of the United States, residing at Denver, in the county of Denver and State 5 of Colorado, have invented certain new and useful Improvements in Milk-Bottle Tops; and I do declare the following to be a full, clear, and exact description of the invention, such as will enable others skilled 10 in the art to which it appertains to make and use the same.

My invention has for its principal object to provide a simply constructed and inexpensive yet a highly efficient and desirable 15 top for milk bottles and the like, embodying a spout through which the contents of the bottle are poured so as to prevent contact thereof with the rim of the bottle which may be more or less soiled and germ-laden.

20 A further object is to provide for venting the top when pouring the contents of the bottle and to make novel provision for closing the vent opening when the top is restored to normal position after partial 25 emptying of the bottle.

With the foregoing in view, the invention resides in the novel features of construction hereinafter fully described and claimed, reference being made to the accompanying 30 drawings.

Figure 1 is a top plan view of the invention applied to a milk bottle.

Fig. 2 is a bottom plan view of the bottle top as manufactured.

35 Figs. 3 and 4 are sectional views on the planes indicated by the lines 3-3 and 4-4 respectively of Fig. 1.

Fig. 5 is a sectional view showing the bottle top opened and the spout positioned 40 for pouring.

In the drawings 1 designates the bottle top which is formed of a one-piece disk of oiled cardboard or of any other appropriate material, said disk having a weakened hinge 45 line 2, whereby substantially one-half 3 of the disk may swing upwardly to open position while the other part 4 will remain stationary within the seat 5 at the top of the bottle neck, the disk being forced into the 50 seat by hand or by an automatic capping machine in the usual manner.

A curved strip 6 of any preferred material is located at the under side of the disk section 3 and at its ends is secured thereto 55 at 7, one end being preferably integral with the disk. The strip 6 forms a spout as seen

in Figs. 3 and 4, and when the disk half 3 is opened by means of a suitable tab or the like 8, the spout is adapted to spring into engagement with the seat 5 as shown in Fig. 60 5, thus providing for emptying the contents of the bottle without allowing them to come in contact with the neck. For facilitating pouring, the bottle top may be pierced with a vent 12 as seen in Fig. 5 and 65 if the top is closed after partial emptying of the bottle, the vent will be sealed by the tongue 11, to prevent entrance of dust, etc.

The tongue 11 is formed by the material bounded by a U-shaped slit 10 formed part 70 way through the fixed half 4 of the top.

By constructing the device as shown and described, or in any other equivalent manner, it will be highly efficient and in every way desirable, particular emphasis being 75 laid upon the following points. First, the spout is confined within the bottle and cannot in any way become soiled or contaminated; second, the spout springs freely into place when the swinging half of the top is 80 opened; third, in emptying the contents of the bottle, they pass only through the clean spout and do not come in contact with the rim of the bottle neck which may be soiled and covered with dust and germs; fourth, 85 the air vent is sealed if the contents of the bottle are not all discharged at once and the top is again closed; fifth, it is not necessary to remove the top and place it on an often dirty table or the like while emptying the 90 bottle; and sixth, the device may be easily and inexpensively manufactured and marketed and may nest with one spout in another to allow compact stacking and use in automatic capping machines. 95

Since excellent results can be obtained from the details shown and described, they may well be followed, but numerous minor changes may be made without departing from the spirit or sacrificing the advantages 100 of the invention as claimed.

I claim:

1. A milk bottle top comprising a disk adapted to be forced into the top seat of a milk bottle neck, said disk having a weakened hinge line to permit substantially half of the disk to swing upwardly, and a curved spout carried by the lower side of said upwardly swinging disk half, normally confined in the bottle neck, and adapted, when 110 said half is raised, to spring into the aforesaid seat.

2. In a milk bottle top, a disk adapted to be forced into the top seat of a milk bottle neck, said disk having a weakened hinge line to permit upward swinging of substantially half of said disk, and a spout carried by the lower side of said disk half and adapted, when said half is opened, to spring into engagement with said seat, said disk having in its lower side a U-shaped cut 5 forming a tongue movable downwardly when said disk half is raised, the disk being adapted to be pierced over said tongue to form an air vent and said tongue closing said vent when said disk half is lowered.
- 10 3. In a milk bottle top, a disk adapted to

be forced into the top seat of a milk bottle neck, said disk having a weakened hinge line to permit upward swinging of substantially half of said disk, the lower side of the other part of said disk having a U-shaped slit forming a tongue extending from the hinge line and movable downwardly when said disk half is raised, the disk being adapted to be pierced over said tongue to form an air vent and said tongue closing 25 said vent when said disk half is lowered.

In testimony whereof I have hereunto set my hand.

JOHN THOMAS COONEY.
